UNITED STATES PATENT OFFICE.

LEO KIMBALL STAFFORD, OF LAWTON, MICHIGAN, ASSIGNOR OF ONE-HALF TO
JUSTUS S. STEARNS, OF LUDINGTON, MICHIGAN.

ROLLER-BEARING JOURNAL-BOX PEDESTAL FOR ARCH-BAR TRUCKS.

Application filed June 23, 1924. Serial No. 721,933.

To all whom it may concern:

Be it known that I, LEO K. STAFFORD, a citizen of the United States, residing at Lawton, in the county of Van Buren and

5 State of Michigan, have invented new and useful Improvements in Roller-Bearing Journal-Box Pedestals for Arch-Bar Trucks, of which the following is a specification.

10 My present invention has reference to a roller bearing journal box pedestal for arch bar trucks.

My primary object is a particular and peculiar construction of pedestals for this purpose whereby roller bearing journal boxes may be easily and quickly secured to the arch bar truck and held firmly thereon in a manner which will permit a limited movement of the box so that the same will be at 20 all times in alignment with the journal.

15 A further object is the provision of pedestals for the arch bar trucks of roller bearing journal boxes which engage the sides of the journal box in such manner as 25 to positively prevent the lateral movement of the box, and wherein the nuts engaged by the securing bolts are pocketed in such a manner that the liability of unscrewing of either the nuts or bolts is reduced to a minimum, and consequently to produce a 30 structure of this character wherein the liability of breakage or separation of parts is reduced to a minimum, and consequently a greater safety to the rolling stock is insured.

35 It is a still further object to produce a pedestal for roller bearing journal boxes for arch bar trucks which may be readily arranged upon different standard sizes of 40 trucks and journal boxes.

A still further object is the production of a device of this character which may be both easily and expeditiously attached to the arch bar frame to positively hold the journal box therein, and which may be likewise as readily removed from the truck 45 should occasion require.

To the attainment of the foregoing and other objects which will present themselves 50 as the nature of the invention is better understood, reference is to be had to the drawing which accompanies and which forms part of this application.

55 In the drawing:—

Figure 1 is a front elevation of the roller

bearing journal box mounted in an arch bar frame in accordance with this invention.

Figure 2 is a sectional view on the line 2—2 of Figure 1.

Figure 3 is a perspective view of one of 60 the pedestals.

My improvement is particularly designed for employment in connection with the type of roller bearing journal boxes which form the subject matter of my U. S. patent application, Serial No. 704,822, filed April 7, 1924.

As disclosed by the drawing, my journal box, indicated by the numeral 1, has its sides formed with longitudinal recesses, and the side walls provided thereby are gradually widened from the ends to the center thereof, as indicated by the numeral 2 (Figure 2). Also the top of the box is centrally formed with enlargements 3 and 4 respectively, there being shoulders 5 provided between the sides and the enlargements 3 and 4. Also there is a step portion between the shoulders and the said enlargements 3 and 4.

Designed to be received in each of the side 80 depressions of the box 1 is the central straight portion 6 of pedestals in accordance with my invention. The pedestals are of a width almost equaling the rounded central portions 2 provided by the recesses 85 in the sides of the box, and the ends of each pedestal 6 is flanged inwardly, as at 7, the said flanges having their ends received in the referred to notched portions of the enlargements 3 and 4. The ends of the pedestals, however, do not contact with the 90 ends of the said portions 3 and 4.

Resting directly on the upper flanges of the pedestals 6 there is the lower arched bar 8 of the truck, the upper arch bar 9 95 resting directly upon the lower arch bar. The tie bar of the frame indicated by the numeral 10 underlies the lower flanges 7 of the pedestals 6. The arch bars 8 and 9 and the tie bar 10 are provided with aligning 100 openings spaced to accord with the different standard size of arch bar trucks, and, of course, my improved roller bearing journal box is constructed of different sizes to accommodate the different standard sizes 105 of the arch bar truck. The ends 7 of the pedestal 6 are provided with bolt openings 10'.

On the inner face of each of the pedestals there is a nut 11. These nuts are received 11

on the shoulders 5 and are received in the pockets 12 provided between the notched corners of the journal box frame and the outer sides of the pedestals. The nuts 11 do not rest directly upon the angle ends of the pedestals, but upon lock washers 13. Passed through the referred to openings in the bars of the truck frame, and likewise through the openings 10' in the ends of the pedestals and threadedly engaging the nuts 11 are the shanks of bolts 14. The heads of the bolts are, of course, arranged on the outer face of the upper arch bar and on the outer face of the tie bar 10, so it will be noted that when the nuts 11 and the split washers 13 are positioned in their pockets the bolts 14 may be readily screwed to engage the said nuts. The frictional engagement exerted between the angle ends of the pedestals and the nuts will hold the bolts 14 from turning. The nuts 11 cannot turn because of their ends or facets being disposed in close proximity to the walls provided by the pockets 12.

With my improvement it will be noted that the pedestals may be easily and expeditiously connected to the truck and will effectively hold the roller bearing journal box therein. It will be further noted that the improvement is of an extremely simple construction, and may be cheaply manufactured. Also it will be apparent that the bolts 14 cannot only be readily turned to engage with the nuts but may be likewise easily turned and unscrewed therefrom so that the pedestals may be removed should for any reason it be desired to remove the roller bearing journal box. It is, of course, apparent that the journal box may be positioned by simply removing the outer pedestal, and it is thought that the simplicity and advantages of my construction will be apparent to those skilled in the art to which such inventions relate.

Having described the invention, I claim:

1. In combination with an arch bar truck and a roller journal bearing box to be supported therein, of pedestals between the upper and lower members of the truck and against the sides of the journal box, and means securing the pedestals to the truck held in locked position by contacting engagement between the pedestals and the journal box.
2. In combination with an arch bar frame and a roller bearing journal box therefor, of pedestals between the upper and lower bars of the truck frame, loosely received in the sides of the journal box, means removably securing the pedestals to the arch bar truck, and said means being held in locked position by contacting engagement between the corners of the journal box and the pedestals.

3. In combination with an arch bar truck, and a roller bearing journal box having its upper and lower portions contacted by the bars of the truck, and said journal box having its sides recessed, of pedestals between the upper and lower bars of the truck frame received in the recesses of the sides of the journal box, means removably connecting the pedestals to the upper and lower members of the arch bar frame, and means associated with said connecting means received between the corners of the journal box and the sides of the pedestals for holding said connecting means in locked position.

4. In combination with an arch bar frame and a roller journal box therein having its upper and lower edges contacted by the frame, said journal box having its corners stepped and its sides recessed, of pedestals between the upper and lower bars of the frame including straight portions which are received in the recessed sides of the journal box, and inwardly directed angle portions which are in contacting engagement with the upper and lower bars of the frame, headed bolts passing through the bars of the frame and the angle ends of the pedestals, nuts for the bolts received between and in the path of contact with the corners of the journal box and the sides of the pedestals, and split spring washers around the bolts exerting a pressure between the angle ends of the pedestals and the nuts.

5. In combination with an arch bar truck frame and a roller journal box carried thereby and having its top and bottom, at the center thereof, contacting the upper and lower bars of the frame, of pedestals having angle ends in contacting engagement with the upper and lower bars of the frame and the center thereof freely received in the sides of the journal box, bolts passing in opposite directions through the upper and lower bars of the frame and through the angle ends of the pedestals, nuts housed between the pedestals and the journal box engaged by the bolts, and spring means surrounding the bolts and exerting a tension between the angle ends of the pedestals and the nuts.

6. The combination with an arch bar truck frame, of a journal box between the upper and lower members thereof, pedestals between said members and at the sides of the box for holding the latter in said truck frame, and bolts for securing the ends of the pedestals to the truck members with the clamp nuts of said bolts held from turning by the pedestals and the box.

7. The combination with an arch bar truck frame, of a journal box between the upper and lower members thereof, pedestals between said members and at the sides of the box for holding the latter in said truck frame, said pedestals having inturned ends,

and bolts for securing the inturned ends of the pedestals to the truck members, said box having recesses at the ends of the pedestals to form with the inturned ends 5 thereof pockets to receive the clamp nuts of the bolts and hold said nuts against turning.

8. The combination with an arch bar truck frame, of a journal box between the upper and lower members thereof, pedestals 10 between said members and at the sides of the box for holding the latter in said truck frame, said pedestals having inturned ends, and bolts for securing the inturned ends of the pedestals to the truck members, said box 15 having two sets of recesses, one set to receive the inturned ends of said pedestals and the other set to form pockets with the

pedestals for the clamp nuts of the bolts and hold said nuts against turning.

9. The combination with an arch bar 20 truck frame, of a journal box between the upper and lower members thereof, pedestals between said members and in grooves in the sides of the box for holding the latter in said truck frame, said pedestals having in- 25 turned ends, and bolts for securing the pedestals to the truck members, said bolts passing through the inturned ends of the pedestals and terminating at the grooved portions of the box with the clamp nuts on 30 said bolt ends.

In testimony whereof I affix my signature.

LEO KIMBALL STAFFORD.
